UNITED STATES PATENT OFFICE.

ANNA DORA THIEME, OF HANNOVER, GERMANY.

COLLAPSIBLE PACKING CASE OR THE LIKE OF SHEET METAL.

Application filed August 2, 1924. Serial No. 729,916.

To all whom it may concern:

Be it known that I, Miss ANNA DORA THIEME, merchant, citizen of the German State, residing at Hannover, Germany, have 5 invented certain new and useful Improvements in Collapsible Packing Cases or the like of Sheet Metal, of which the following is a specification.

Collapsible sheet metal packing cases, 10 boxes and the like, the walls of which are held together by beadings, that are capable of being slid one into the other, are known. The subject of this invention is a collapsible container of sheet metal, which is particu- 15 larly easily and firmly put together and very easily taken to pieces again. In the new collapsible packing case or the like of sheet metal two opposite edges of the bottom are provided with inwardly (upwardly) bent 20 rolled beadings, for forming a connection with two opposite side walls by means of corresponding beadings formed by the inwardly bent lower edges of the sides being rolled over to the outside. These side walls, 25 the upright edges of which are provided with similar beadings, are connected to the other side walls by corresponding beadings, the lower edges of which are provided with beadings bent over at right angles, which 30 are covered by similar beadings formed from the bottom of the case.

The corners formed by the side walls can be supported by angle-shaped clamping members, which are preferably so constructed, that in a piece of sheet metal, one angle of which is a right angle, the edges containing the right angle are beaded over so as to fit the inwardly beaded-over upper edges of the side walls of the sheet metal container. 35

It depends more particularly on the shape of the rolled-over beadings, whether the collapsible sheet metal container will hold firmly together or not. The inwardly bent edge is rolled over so far to the outside and 40 the corresponding beading is rolled over so far to the inside, that it is impossible to take the two beadings apart from the side and that the parts can only be put together and taken apart by sliding one beading on to or off the other.

The invention is clearly illustrated in the accompanying drawings, in which:—

Fig. 1 being a perspective view of the complete container with the cover partly broken away,

Fig. 2 a vertical section on line A—B of Fig. 1,

Fig. 3 a vertical section on line C—D of Fig. 1,

Fig. 4 a transverse section on line E—F of Fig. 2,

Fig. 5 shows the container taken to pieces with the separate parts in section,

Fig. 6 shows a corner joint, and

Fig. 7 a bottom corner connection in perspective to an enlarged scale.

In the constructional example shown the bottom *a* is provided on two opposite edges with open beadings *b*, which are rolled inwards from the side, the other two edges *c* of the bottom being bent upwards at right angles. Two of the side walls *d*, *e*, *f*, *g*, for instance the side walls *d* and *f* are provided at the bottom edge and all the side walls are provided at both lateral edges with similarly rolled beadings *h*, *i*, *k*, which are so formed that the beadings *h* of the lower edges of the side walls *d*, *f* may be slid lengthwise into the beadings *b* of the bottom part *a*, while the beadings *i*, *k* at the lateral edges of the walls *d*, *e*, *f*, *g* are adapted to be slid into one another. The lower edges of the side walls *e*, *g*, which lie along the bent up edges *c* of the bottom part, have horizontally bent up edges *m* in place of the 75 rolled beadings, with which they rest on the bottom part *a*, while the bent up edges *c* of the bottom part embrace the walls *e*, *g* from the outside, thus making a tight joint.

All the rolled beadings, when slid into 90 one another, give the container a certain rigidity. In order, however, to make the container absolutely rigid and to exclude the possibility of the walls becoming displaced, when the container is in use, corner 95 clamps *n* are provided at the upper corners of the side walls *d*, *e*, *f*, *g*, the edges of which are beaded over so as to embrace the upper edges of the side walls, which may also be beaded over. These corner clamps *n* 100 may be clamped in overlapping relation to the upper beaded edges of the side walls or if desired soldered to the upper bead of one side wall and their limbs may be rigidly connected by a flat bridging member *o* 105 as a stiffening member. An ordinary beaded over lid *p* forms the cover of the container.

I claim:

A collapsible packing container of sheet 110

metal including a bottom and side walls, upwardly and inwardly rolled beads continuing from two opposite edges of the bottom, upstanding flanges continuing from the 5 two remaining opposed edges of the bottom, inwardly, downwardly and upwardly rolled beads continuing from the lower edges of the two opposed side walls for lateral sliding engagement with the beads 10 on the bottom for connecting the said side walls to the bottom, inwardly extending flanges continuing from the lower edges of the remaining side walls for contacting engagement with the bottom, interengageable 15 rolled beads continuing from the lateral edges of all of the side walls and adapted for vertically slideable engagement with each other, the beads on the lateral edges of two opposed side walls extending inwardly, outwardly and thence inwardly between the 20 first two folds while the beads on the outer

edges of the remaining opposed side walls extend inwardly and outwardly adjacent the main portion so that the parts will be interlocked subsequent to the said vertical 25 sliding engagement, inwardly rolled beads continuing from the upper edges of the side walls, angle clamps for clamping the upper corners of the side walls forming the box, including angularly disposed beaded portions 30 for overlapping engagement with the beads on the side walls, and a bridging portion connecting said beaded portion and a flanged cover for frictional engagement with the upper portion of the side walls for 35 closing the container.

In testimony whereof I affix my signature in presence of two witnesses.

ANNA DORA THIEME.

Witnesses:

Dr. HELLMUT BOECKLEY,
ELSE FISCHER.
